CLOSURE FOR BOTTLES OR THE LIKE

William Worsley, East Grinstead, Sussex, England, assignor to Wicanders (Great Britain) Limited, a company of Great Britain

Filed Aug. 10, 1961, Ser. No. 66,287

Term of patent 7 years

(Cl. D58—10)

FIG. 1

FIG. 2

FIGURE 1 is a top perspective view of a closure for bottles or the like embodying my new design;

I claim:

The ornamental design for a closure for bottles or the like, as shown.
